UNITED STATES PATENT OFFICE.

JOHN CANNON WATKINS, OF VANCOUVER, BRITISH COLUMBIA, CANADA.

ICE-CREAM CABINET.

Application filed May 27, 1926. Serial No. 112,119.

My invention relates to improvements in ice cream cabinets, the objects of which are to provide means whereby the cooling medium is not dissipated when the can lids are removed. A further object is to provide a collapsible sleeve which is adapted to extend between each opening in the top of the cabinet and the top of each of the cans.

One form of the invention consists of a sleeve having a support extending from one side to another to which a lever is hingingly connected and which is adapted to extend the circumferential length of the sleeve to fit the can top and the top opening of the cabinet, as will be more fully described in the following specification, in which:—

Fig. 1 is a sectional view of a three hole ice cream cabinet having the collapsible sleeves fitted therein.

Fig. 2 is a plan view showing the sleeve fully expanded.

Fig. 3 is a plan view showing the sleeve fully contracted.

Fig. 4 is a fragmentary view of a modification of the collapsible sleeve.

In the drawings like characters of reference indicate corresponding parts in each figure.

The numeral 1 indicates an ice cream cabinet which is suitably insulated with cork, dead air spaces or otherwise and preferably having an impervious inner lining 2, such as galvanized iron, to its side walls 3 and bottom wall 4, which latter is usually provided with a drain pipe 5. The numeral 6 indicates the perforated sleeve resting upon the bottom wall 4 which is adapted to receive an ice cream can 7 and to keep the ice, when crushed ice is used as a cooling medium, from forming an obstruction to the insertion of a filled can after an empty one has been removed. The ice is usually filled into the cabinet to approximately the top level of the sleeve 6. The cabinet is usually fitted with a cover 8 having circular openings 9 corresponding in number to the cans contained therein, which openings are provided with suitable lids 10. Between the upper extremity of each can and the opening 9 of the cover 8 a collapsible sleeve, generally indicated by the numeral 11 is detachably fitted. The sleeve 11 consists preferably of relatively broad band 12 of sheet metal bent into cylindrical form having its

opposite ends normally overlapping as at 13. 55 Adjacent one end a spring 14 is riveted, the free end of which is adapted to extend beyond the joint of the sleeve and to bear upon its inner periphery adjacent the opposite end of the sleeve as at 15. Secured at 60 substantially diametrically opposite points on the inside of the sleeve 11 is a semi-cylindrical strip forming a support 16. A lever 17 having a roller 18 at its opposite end which is adapted to bear upon the spring 65 14, is hingingly connected as at 19 to the support.

In the modified form of construction of the collapsible sleeve the band is provided with overlapping ends 20 and 21 respectively. On the end 21 and preferably adjacent its lower inner face, a bracket 22 is riveted, between the jaws of which a pinion 23 is mounted, this pinion is adapted to operatively engage a rack 24 mounted upon the 70 inner face of the end 20 and is provided with a lever 25 by which it is turned to contract or expand the band. The pinion is somewhat tightly gripped between the jaws of the bracket to provide such resistance to its 75 turning, that it will remain in any position in which it is set.

Having thus described the several parts of my invention I will now briefly explain its use.

Ice or other cooling medium is placed in the cabinet surrounding the perforated sleeve 6, and ice cream cans 7 are then placed within the sleeve. Their covers (not shown) are removed, and sleeves 11 which have been 85 previously collapsed as shown in Figure 3, with levers projecting towards the centre of the sleeve so as to permit of the opposite ends thereof overlapping, are inserted through the openings 9 into the top of the cans 7, the sleeves being so positioned that their upper faces are level with the upper surface of the cover 8. The levers 17 are then swung over to lie in contact with their supports 16, the rollers 18 being brought into 90 forcible contact with the spring 14, which causes the diameter of the sleeves to be increased as shown in Figure 2, thus securing them firmly in position between the top of the cans and the openings 9 in the covers 8. 95 When the sleeves are so placed the cold air within the cabinet is prevented from escape through the openings 9 of the cover 8 and 100 105

consequently access can be obtained to any one of the cans 7 without impairing the cooling effect of the ice.

What I claim as my invention is:

- 5 1. In an ice cream cabinet having a cover provided with an opening and in which an ice cream can is adapted to be positioned, means forming an extension between the can top and the opening, said means comprising a band of sheet material forming a cylindrical body with its opposing ends overlapping, and means for expanding the band to engage the can top and the rim of the opening within the cover.
- 10 2. In an ice cream cabinet having a cover provided with an opening and in which an ice cream can is adapted to be positioned, means forming an extension between the can top and the opening, said means comprising a band of sheet material forming a cylindrical body with its opposing ends overlapping, a lever supporting member connected at substantially diametrically opposite positions

within the band, a lever pivoted to said member and means as the lever is operated 25 for expanding the band.

3. A device of the character described comprising a cabinet adapted to receive therein a cooling medium, an ice cream can of less height than the cabinet contained therein, a cover for the cabinet provided with an opening positioned directly above the mouth of the can, a lid for said opening and an expandible and collapsible collar having one end fitting within the mouth of the 30 can and the other end fitting within the opening of said cover.

4. A device as recited in claim 3 in which the expandible and collapsible collar comprises a split metal band and lever operated 35 means carried thereby for effecting expansion and contraction.

Dated at city of Vancouver, Province of British Columbia, 13th day of May, 1926.

JOHN CANNON WATKINS.
